DEISTER MACHINE COMPANY, OF FORT WAYNE, INDIANA, A CORPORATION OF
INDIANA.

CONCENTRATING TABLE

Application filed September 11, 1924. Serial No. 737,085.

The invention relates to concentrating tables in general and is directed primarily to a combined feed distributing and preliminary concentrating apparatus designed 5 to operate in conjunction with concentrating tables.

The object of the invention is to provide a concentrating table with novel means by 10 which materials may be fed in partially concentrated form onto the table, thereby facilitating and expediting the separation of the heavier from the lighter material and increasing the capacity of the table and securing a highly efficient concentrating apparatus especially adapted for the cleaning 15 of coal.

The invention consists of an auxiliary deck mounted on a transversely inclined differentially reciprocated table, the auxiliary 20 deck being transversely inclined in a direction opposite to the inclination of the table and adapted to receive the materials and deliver them in partially concentrated form on the table adjacent the upper or feed side 25 of the latter.

An embodiment of the invention is illustrated in the accompanying drawings in which Figure 1 is a plan view of a concentrating table having the invention applied thereto; Fig. 2 a cross-sectional view 30 on line 1—1 of Fig. 1; Fig. 3 a cross-sectional view on line 3—3 of Fig. 1; Fig. 4 a cross-sectional view on line 4—4 of Fig. 1; Fig. 5 an end view of the mechanism 35 taken at the head end of the same; Fig. 6 a fractional cross-sectional view on line 6—6 of Fig. 1 and Fig. 7 a cross-sectional view on line 7—7 of Fig. 5.

In the illustrative embodiment of the invention 40 1 represents the main deck of a concentrating table having the riffles 2 on its upper surface extending from the head end 3 of the deck toward the concentrates discharge end 4. The deck is inclined downwardly from the feed side 5 toward the tailings discharge side 6. Suitable mechanism 7 at the head end 3 of the deck and suitably connected to it is adapted to differentially reciprocate the deck in a direction substantially parallel to the riffles 2.

The deck is supported for longitudinal reciprocation upon the bearings 8 of suitable form.

An auxiliary deck 9, preferably somewhat triangular in shape, is disposed above the 55 deck 1 and adjacent to the upper side and to the head end thereof. As shown in Fig. 5, the auxiliary deck is suitably pivoted at 10 to the head board 11 of the deck 1. The pivot (Fig. 7) comprises a casting 12 secured to the main deck by the bolts 12^a. The upper end of the casting is bifurcated to form a socket 13 for supporting an apertured boss 14 that projects from a casting 15 bolted to the auxiliary deck. A bolt 16 60 is projected through the apertured boss, the casting 15 and the frame of the auxiliary deck and a nut 17 on the outer end of the bolt 16 when tightened against a washer 17^a forces the washer against the opposed face 70 of the casting 12 and thereby locks the auxiliary deck to the main deck. A bar 18 is secured to the head board 11 by the bolts 19, the bolts being laterally adjustable in slots 20 in the board when the nuts 21 are 75 loosened. The upper end of the bar 18 is slotted to receive a bolt 22 projecting from the head end of the deck 9 and it is also transversely corrugated as shown at 18^a. A washer 23 on the bolt 22 secures the bar 80 to the deck 9 when the nut 24 is tightened, the rear face of the washer being provided with teeth for engaging the corrugations on the bar 18. The washer tends to support the upper side of the deck 9 when the nut 24 85 is loosened so that adjustment of that deck is readily accomplished. The inclination of the deck 9 is the reverse of that of the main deck 1 and when it is properly adjusted the bar 18 maintains the relative positions of the two decks. The opposite end or apex of the deck 9 is pivoted to the side board 25 of the main deck, the pivot being formed by an apertured socket plate 26 secured to the side board 25, in which socket 95 is the head 27 of a bolt 28 and washer 29, the bolt being extended transversely through the aperture 30 in the plate 26, through a bearing 31 and through the adjacent end of the deck 9 and held tight by a nut 32 on the 100

opposite end of the bolt. The socket-forming portion of the plate 26 is convex and the opposing face of the bearing that contacts with the convex portion of the plate 26 is concave. By loosening the nut 32 and the nut or nuts that cooperate with the bar 18 and the nut 17 the deck 9 may be adjusted as to its inclination, and after the adjustment has been made and the nuts tightened the deck is rigidly held in position on the deck 1 and reciprocates with it.

Ruffles 33 are disposed on the deck 9 at any desirable angle with respect to the direction of reciprocation of the decks. The material to be treated is fed to the auxiliary deck 9 in the space 34 adjacent to the upper end of the diagonal side of the deck 9. A dressing water board 35 extends along the latter side from the space 34 toward or to the apex or forward end of the deck 9. This board is secured directly to the top surface of the deck. Gates 36 may be mounted on the board to control the distribution of the dressing water onto the deck 9.

A dressing water launder 37 is mounted at the upper side of the main deck 1 and preferably extends from the forward end of the deck 9 to the concentrates discharge end 4 of the main deck.

In operation, with the auxiliary deck properly adjusted as to transverse inclination and the driving mechanism differentially reciprocating the two decks, the materials to be treated and mixed with water are fed onto the space 34 of the auxiliary deck 9 and under the influence of gravity they tend to flow down the inclined surface of that deck toward the discharge edge 38. The ruffles catch the heavier particles and the lighter particles pass over the ruffles. The reciprocating movement of the deck conveys the heavier particles in the riffle troughs onto the smooth surface 39 adjacent the ends of the ruffles, the dressing water removing the lighter particles more or less from the caught materials and washing them over the ruffles and finally over the discharge edge 38 onto the main deck 1. The heavier particles travel down the smooth or unriffled surface 39 and discharge over the edge 38 onto the main deck 1 in advance of the lighter materials, so that they are immediately caught by the ruffles on the main deck and conveyed toward the discharge end 4 of that deck. The lighter materials drop onto the main deck rearwardly of the heavier particles and flow down the inclined surface of that deck, the ruffles catching more and more of the heavier materials and guiding them under the influence of the reciprocating movement of the decks toward the discharge end 4. The dressing water flowing from the launder 37 is controlled by the gates 40 mounted on the launder, and it removes from the caught materials such lighter ma-

terials as will wash out of the riffle troughs, the lighter materials eventually passing over the discharge side 6 of the main deck 1.

The heavier particles reaching the discharge end 4 of the main deck 1 are the waste materials, or slate when coal is treated and which in very large measure are free from lighter materials, such as coal.

The auxiliary deck spreads out the feed and delivers it to the main deck along a large portion of its upper side, the materials being separated by the auxiliary deck so that the heavier materials are deposited on the main deck much nearer to the concentrates discharge end of that deck than the lighter materials and the remainder of the feed is deposited on the deck rearwardly of the heavier materials and more or less in the order of their specific gravities.

We therefore obtain, by the auxiliary deck, a partially concentrated feed for the main deck and we are thereby enabled to remove the heavier particles rapidly on the main deck and materially increase its capacity and efficiency.

When the table is used to clean coal the coal particles pass off the main deck along the side 6 and the waste materials at the end 4 thereof; whereas, when the table is used as an ore concentrator the values pass off the table at the end 4 and the waste materials at the side 6.

What we claim is:

1. The combination with a transversely inclined riffled concentrating table, of an auxiliary triangularly shaped deck pivotally mounted on the table at the upper rear corner thereof, said deck being transversely inclined in a direction opposite to the transverse inclination of the table, longitudinal riffles on the deck, a dressing water board secured to the surface of the deck along the diagonal side of the deck and gates pivoted to the board along the lower side edge thereof to control the discharge of dressing water from the board to the deck.

2. The combination with a transversely inclined riffled concentrating table having a side board along its upper side, of an auxiliary triangularly shaped longitudinally riffled deck, a socket member secured to the deck adjacent to the apex of the deck, a spherical member secured to the side board and engaged in the socket member, a pivot disposed in the longitudinally opposite corner of the deck and mounted on the table and means adjustably engaging the remaining corner of the deck and mounted on the table for adjusting the transverse inclination of the deck.

3. The combination with a transversely inclined concentrating table, means at one end of the table for differentially reciprocating the table, a triangularly shaped auxiliary deck transversely inclined in a direc-

tion opposite to the inclination of the table, riffles on the auxiliary deck substantially parallel to the line of reciprocation of the table, pivotal members secured to the upper and rear sides of the table and engaging the auxiliary deck adjacent to opposite ends of its discharge side, a slotted upstanding member mounted on the rear end of the table, means on the rear end of the deck 10 adapted to secure the slotted member to the

deck in various inclined positions of the deck and a dressing water board secured to the top surface of the deck and extending along its diagonal upper side.

In witness whereof we have hereunto subscribed our names this 28th day of August, 1924.

WILLIAM F. DEISTER.
EMIL DEISTER.
